ABSTRACT OF THE DISCLOSURE

A furnace having a sealed shell and means for evacuating said shell. A rotatable hearth having at least one mold cavity within said shell and an adjustable plasma torch having a discharge nozzle located within said shell to direct the effluent onto said hearth.

This invention relates to a furnace for melting buttons or small ingots of metals. It is particularly adapted for melting refractory metals which require melting at arc temperatures and which are also reactive at elevated temperature requiring melting in a protective or inert atmosphere.

Small button furnaces, as they are called, are most often used to melt small circular discs or buttons of experimental alloys or for melting samples of metals for analytical purposes. In addition to discs, pillow-shaped small ingots, as well as bars, may be produced. An arc furnace has most often heretofore been employed using a non-consumable tungsten electrode to melt a small amount of metal in a cavity in a water-cooled hearth. The furnace may be maintained under vacuum or filled with inert gas to prevent contamination of the melted metal by atmospheric gases, particularly oxygen and nitrogen.

It is difficult, however, to obtain desired purity of melted metal in such a tungsten electrode furnace. A melting arc is often erratic, causing spatter of metal from the mold cavity, and this may contaminate metal in adjacent cavities if a multiple cavity hearth is used. Of more importance is the tendency of metal to spatter onto the tungsten electrode itself, and when this becomes molten or falls off as solid, it carries tungsten contamination with it. Contamination from the tungsten electrode is a serious disadvantage of this type of melting.

Summarized briefly, the furnace of this invention operates with a heat source providing a steady and controllable stream of arc plasma. This avoids problems associated with a melting arc as heretofore known and used. It avoids possible contamination by tungsten from the electrode and enables a plurality of cavities to be arranged in close proximity in a hearth without danger from contaminating spatter. Use of a plasma jet torch provides a stable effluent that can readily be directed onto a sample or mass of metal to be melted. The torch operates with a tungsten electrode, but this is placed up inside a barrel and protected by the nozzle as well as the high speed plasma effluent. Under these conditions, spatter onto the tungsten electrode is eliminated as is tungsten contamination in the melt from this source.

The steady and readily controlled plasma effluent also eliminates or reduces spattering from the molten pool of metal being melted. Therefore, closely spaced cavities in a multiple cavity hearth may be employed; and only minimum, if any, shielding between cavities is required.

The plasma jet torch requires an inert gas flow to provide a hot, gaseous effluent. This results in a continuing inflow of inert gas into the furnace during operation, and provides an ideal atmosphere in the furnace for melting reactive metals. Thus, the required inert gas atmosphere

2

is automatically maintained in the furnace during operation. The furnace of this invention will be more clearly understood by reference to the following more detailed description thereof, and to the drawings, in which

FIG. 1 shows a side view, partly broken out, of a furnace embodying features of this invention;

FIG. 2 shows a horizontal cross section of the furnace of FIG. 1 taken along the line 2—2;

FIG. 3 shows in detail the furnace view-port and its protective screen;

FIG. 4 shows in detail the furnace hand-hole and cover;

FIG. 5 shows a cross section of the hand-hole of FIG.

4 taken along the line 5—5; and

FIG. 6 shows details of the plasma jet torch.

Referring now particularly to FIGS. 1 and 2, the furnace comprises a supporting base composed of uprights 10, lower horizontal bars 12 and upper horizontal bars 14. On the top of upper horizontal bars 14 is attached furnace lower plate 16 to which the furnace shell 18 is attached and sealed thereto by "O" ring 20. Furnace shell 18 is generally hemispherical at its top and encloses the furnace working parts, as will be hereinafter described in detail. It is constructed so as to be gas-tight or sealed to prevent entry thereinto of atmospheric gases.

Vertically mounted drive shaft 22 passes through furnace bottom plate 16, its passages being sealed by rotatable seal and thrust bearing 24. Drive shaft 22 is hollow, carrying a central water inlet tube 26 to which is connected at its bottom cooling water supply line 28. The annular space between bottom pipe 26 and the interior surface of shaft 22 provides a channel for outflow of cooling water, which may be discarded to a suitable drain through drain pipe 30.

Vertical shaft 22 is rotated by means of encircling gear 32, fixedly attached to the exterior surface of vertical shaft 22, which meshes with worm 34, which is rotated at desirable speed by speed reducer 36 connected to the output shaft of motor 38. Support bracket 40 supports motor 38 in proper position for connection of the drive train described, and is itself supported on horizontal bars 12.

Rotation when desired of shaft 22 is controlled by pedal switch 42 connected through lead 44 to a suitable source of electric power indicated as power cabinet 45, in turn connected to motor 38 through lead 46.

Fixedly attached to the top of vertical shaft 22 is rotatable hearth indicated at 48 having base 50. Rotatable hearth 48 is provided with an upper heavy circular plate 52, preferably fabricated of copper to take advantage of this metal's heat transfer characteristics. Upper plate 52 is attached to base 50 by edge plate 54 maintained in tight contact top and bottom by peripheral bolts 56. The top and bottom elements of hearth 48 are arranged so that there is spaced for circulation of cooling water therebetween, such cooling water being introduced through pipe 26 and distributed to the edges of hearth 48 by subsidiary pipes 57, the return water flowing through the open space back down through hollow vertical shaft 22 and out drain pipe 30.

Upper plate 52 of hearth 48 is provided with a plurality of indentations or open-top cavities as at 58 into which metal may be melted into ingots or buttons. Cavities 58 may be of various shapes to provide the desired button or small ingot shape, as will be seen more clearly in FIG. 2. These, for example, may be designed as pillow block cavities 58a, circular cavities for producing metal buttons, as at 58b, or bar cavities for producing elongated metal shapes, as at 58c.

In the top of furnace shell 18 is arranged loading port 60 which is closed by provision of cover plate 62. Clamps 64 maintain cover plate 62 firmly attached to rim 66 of port 60, the connection being sealed by O ring 68. Light bulb 70 is located in a receptacle 72 in cover plate 62 to

provide illumination for the interior of the furnace during loading, unloading and other periods when illumination is not provided by discharge from the torch.

Also in the top of furnace shell 18 is arranged viewport 74 whose extending tube 76 is spanned by protective screen 78 and closed at its outer end by window 80. The details of this construction are shown more clearly in FIG. 3.

The hand-hole arrangement, by which articles inside the furnace may be manipulated without affecting the furnace atmosphere seal, is shown in detail in FIG. 4 and FIG. 5. Handhole tube 82 is provided with gauntlet 84, having a comparatively long sleeve 86 whose free end is fixedly attached to the rim on tube 82 and in sealing engagement therewith. Gauntlet 84 may be fabricated of any suitable flexible and gas impermeable material, such as rubber or plastic and its sleeve end may be attached to the rim of tube 82 by a suitable adhesive and sealant. The end of tube 82 is closed and protected by cover 88, which is hingedly arranged to close the end of tube 82, as by articulated bolts 90. Gauntlet 84 and its sleeve 86 are prevented from ballooning into the interior of the furnace under the effect of vacuum therein by provision of plate 92 which abuts against a ledge formed of spaced segments 94 fixedly attached to the tube wall. When it is desired to work with gauntlet 84 inside the furnace, plate 92 is pivoted to a position parallel with the axis of tube 82 so that it may be slipped edgewise through the spaces between ledge segments 94 and placed temporarily inside the furnace proper, manipulation being accomplished through gauntlet 84. Plate 96 is normally maintained across tube 82 by action of spring clips 98 to act as an additional radiation shield to protect gauntlet 84 and sleeve 86 from heat in the furnace. Plate 96 can be removed from its position as shown, conveniently when plate 92 is edgewise in the tube between ledge segments 94, and both plates may be placed in the furnace temporarily and without breaking the furnace seal by manipulation through gauntlet 84.

Mounted through the wall of furnace shell 18 and sealed as it passes therethrough is a plasma jet torch, indicated generally at 100, whose construction is shown in more detail in FIG. 6. Torch barrel 102 slidably engages ball 104 being sealed as it passes therethrough by flexible bushing 106. Ball 104 is mounted in flexible cupped sealing ring 108, which is in turn fixedly attached to mount tube assembly 110, as by screws 111, which act to tighten clamp ring 112. Torch 100 can therefore be slidably moved up and down through seal bushing 106 and in a variety of pivotal movements through the action of ball 104 in its sealing ring 108. Material which is slightly flexible and which can be compressed to form a tight seal will be suitable for fabrication of bushing 106 and ring 108. Preferably, these elements are fabricated from a plastic fluorinated hydrocarbon, such as manufactured and sold under the trade name Teflon. Such material has self-lubricating properties, as well as functioning adequately as a sealing material.

To the body 110 of plasma jet torch 100 is attached handle bar 113, attachment being accomplished by clamping ring 114. Handle bar 113 is suitably curved and bent so that it may be readily grasped by an operator conveniently seated so that he can view the operation inside the furnace through window 80 and also be in a position to operate the control foot pedals mounted on horizontal bars 12.

One pole of a D.C. electric power source is connected to the electrode of plasma jet torch 100 (as will be seen more clearly in FIG. 6) by means of power lead 116. Cooling water is supplied to the torch through cooling pipe 118 connected to a suitable source of cooling fluid, such as water, such fluid being withdrawn from torch 100 through drain line 120 connected to a suitable sewer or sump, also not shown. Inert gas fitting 121 is connected to torch 100 to supply this gas for its operation.

The weight of plasma jet torch 100 is suitably counter-

balanced so that the operator may readily actuate it up and down and rotatably to put the end of barrel 102 in proper position for melting metal in cavities 58 in hearth plate 52. Counter-balancing is arranged by provision of clamp 122, which is fixedly attached to an upper part of plasma torch body 110, conveniently supporting also water pipes 118 and 120, as shown, the clamp being connected to cable 124, which passes over elevated pulleys 126 and whose free end is attached to counterweight 128.

Since the metal body being melted will, in most cases, also be connected to the source of electric power, a suitable lead 130 is shown attached to shell cover 18 and to plate 16 from which connection will be made through shaft 22 and to hearth 48 and its upper plate 52 and so to metal in a cavity 58. Various power levels are advantageous for best operation of the device, and these may be arranged by inclusion of suitable and conventional equipment in the power cabinet 45 and controlled through lead 132 by pedal switch 134.

The furnace shell 18 will comprise a sealed, gas-tight shell in which metals may be melted without contact with atmospheric gases. Pipe 136 fitted with valve 138 communicates with the furnace interior, as shown, and for initial evacuation may be connected to a suitable pump (not shown). After the furnace interior is evacuated, it may be back-filled with inert gas through valved pipeline 139 to provide a protective atmosphere for melting. This atmosphere will in most cases be maintained by additional inert gas introduced into the furnace shell through plasma jet torch 100. Excess gas may be vented from the furnace interior through bleed pipe 140, whose outlet is submerged in oil bubbler 142, which prevents any back-flow or entry of outside atmosphere gases into the furnace. Thus, after the furnace atmosphere is initially established, it is maintained automatically by the gas normally introduced by the plasma jet torch operation.

Plasma jet torch 100 is of conventional design and is shown in FIG. 6 in sufficient detail for appreciation of its construction and operation in the furnace of this invention. Cooling water introduced in pipe 118 circulates inside the body tube 110 and also barrel 102 with baffle 144 arranged spaced apart from inner wall 146 to provide a return for cooling water circulated back up to the top of the torch to be discharged through pipe 120. The torch central electrode is formed with a tip 148 of heat an corrosion resistant metal such as tungsten, the electrode proper being formed of an outer tube 150 and an inner tube 152. Cooling water from pipe 118 is circulated down the electrode between tubes 150 and 152, being returned through inner tube 152 and discharged through pipe 120. Inert gas is supplied to the torch through fitting 121 from a convenient source (not shown) and provides a flow of inert gas through the annular space 154 between the center electrode and the inner barrel wall 146. When an arc is maintained between electrode tip 148 and metal in a mold cavity 58, the flow of inert gas is converted to a very hot plasma effluent directed out of the nozzle 156 of torch 100 and which is caused to impinge on the metal to be melted.

In operation of the furnace of this invention, clamps 64 are first loosened and then cover plate 62 is removed to open the furnace. Various charges of metals to be melted are then placed in cavities 58 in the upper plate 52 of hearth 48. The masses to be melted may be compacts of powdered or sponge metal, as, for example, titanium or zirconium sponge admixed with various alloying agents, or may be any other kind of metallic material which it is desired to melt into buttons or small ingots. Particular cavities 58a, 58b, or 58c will be selected, depending on the desired shape of the metal button, pillow block, or bar.

The various charges being placed in the hearth cavities, cover plate 62 is then replaced and securely sealed in position by retightening clamps 64. Vacuum line 136 will have been previously connected to a suitable vacuum

pump, which is now started, and valve 138 is opened so that the interior of furnace shell 18 may be evacuated. Care will be taken that the valves in bleed line 139 and oil bubbler line 140 are closed and that all other seals and fittings in and on the furnace are in proper gas-tight engagement. The furnace should be pumped down to a low pressure indicating proper vacuum-tightness of the system. With a normal-sized button furnace of the type described, evacuation to 20 microns pressure will indicate that the furnace is in proper condition for inert gas melting. After a vacuum-tightness check, a leak check should show no more than 5 microns per minute increase in pressure for a 5-minute period; preferably the leak check should show no more than 2 microns per minute for a 5-minute period.

After a satisfactory vacuum check, valve 138 is closed and a suitable inert gas, such as argon, is admitted into the furnace conveniently through valve pipeline 139. With the furnace interior now back-filled with argon, valve 139 is closed and cooling water supply to plasma jet torch 100 is turned on through inlet pipe 118, and argon gas supply is turned on through inlet pipe 121. Cooling water is caused to be circulated through hearth 48 by inflow of water through pipe 28. Operation of pedal switch 134 now turns on power between the electrode in plasma jet torch 100 and the metal charge in a cavity 58 substantially aligned underneath it. This produces a plasma jet effluent from the end of barrel 102, which may be accurately directed upon the metal charge by actuation of handle bar 113 to effect vertical or pivotal movement of torch 100 as desired. After the charge in one cavity 58 is melted, the plasma jet torch power supply may be cut down momentarily to a lower level by operation of pedal switch 134, and then hearth 48 is rotated by operation of pedal switch 42 so as to align another cavity 58 with its contained metal charge underneath the end of plasma torch barrel 102. With the new cavity in position, melting power is again applied to plasma jet torch 100 and effluent is accurately directed to melt the new charge by pivoting or sliding movement of plasma jet torch 100 by actuation of handle bar 113. When the second charge has been melted, the procedure may be repeated until all the charges in the cavities 58 in hearth 48 have been initially melted. During melting, the argon atmosphere inside furnace shell 18 is maintained by argon introduced into plasma torch 94 as plasma-forming gas. Excess argon is vented from the furnace interior through oil bubbler 142.

After initial melting, and to insure homogeneity in the buttons and small ingots, they are best remelted after turning over so that the bottom portions may be exposed to the torch melting heat. To accomplish this, power to plasma jet torch 100 is shut off and cover 88 of hand-hole tube 82 is removed by loosening bolts 90, and the operator then inserts his hand in gauntlet 84 and first places plate 92 edgewise and then places it and plate 96 temporarily inside the furnace shell 18. Then with his gauntlet hand he reaches inside the furnace shell 18 and turns over the initially melted buttons or ingots. This turning is, as will be appreciated, accomplished without admitting air into the interior of the furnace.

After the buttons are turned, the operator, still with his hand working in gauntlet 84, replaces plate 96 and 92. He then places the gauntlet 84 and sleeve 86 in tube 82 extension and replaces cover 88 and tightens this in place by means of bolts 90. Electric power is then applied between the electrode in plasma jet torch 100 and one of the initially melted buttons or ingots in a cavity 58, and this metal button or ingot is then remelted to form a final ingot. After remelting one such button or ingot, the hearth is rotated to align another underneath plasma jet torch 100, and the remelting operation is repeated as before.

After all the buttons and small ingots have been remelted (and if desired remelting may be repeated several

times), plasma jet torch power is shut down by operation of pedal switch 134, and cover plate 62 is removed after first loosening clamps 64. The finished buttons or ingots may then be removed from the furnace.

The melting furnace of this invention is convenient and efficient in operation. The plasma effluent from the torch is more stable than an arc discharge heretofore employed for heating in such furnaces. Since the effluent is directed from the end of the torch barrel as a stream of plasma and gas, it can be pointed and accurately controlled to impinge on the surface of metal in one of the hearth mold cavities. The means for directing this effluent, that is the slideable and pivotable mounting for the torch barrel, enables the operator to accurately control the torch effluent for best melting effect. The plasma jet torch therefore provides a readily and accurately controllable source of intense heat for efficient melting of metal bodies successively in a plurality of mold cavities.

Another unique advantage of the furnace of this invention is the additional feature of maintenance of an inert melting atmosphere inside a sealed furnace shell using the inert gas supplied for operation of the plasma jet torch. I have found that a required amount of inert gas (according to normal operating procedures) for operation of the torch will provide sufficient inert gas passing through the shell, and vented without entry of atmospheric gases, to efficiently maintain a desirable inert gas melting atmosphere inside the furnace shell. This insures that no deleterious oxidation or contamination by reaction with external atmospheric gases will occur. Thus, the inert gas supplied to the torch serves a dual purpose—it provides gas for plasma generation, and also gas for maintenance of a protective atmosphere inside the furnace.

I claim:

1. A furnace for melting metals comprising:

- (a) a sealed shell;
- (b) a rotatable hearth in said shell, said hearth having at least one mold cavity;
- (c) a plasma jet torch having a tip and a nozzle located within said shell, and means to supply inert gas past said tip through said nozzle into said shell;
- (d) means adjustably mounting said torch for directing the effluent from said nozzle onto metal to be melted in a mold cavity in said hearth; and
- (e) means for evacuating said shell.

2. A furnace for melting metals comprising:

- (a) a sealed shell;
- (b) a rotatable hearth in said shell, said hearth having a plurality of mold cavities;
- (c) a plasma jet torch having a tip and a nozzle located within said shell, and means to supply inert gas past said tip through said nozzle into said shell;
- (d) means adjustably mounting said torch for directing the effluent from said nozzle onto metal to be melted in a mold cavity in said hearth; and
- (e) means for evacuating said shell.

3. A furnace for melting metals comprising:

- (a) a sealed shell;
- (b) a rotatable hearth in said shell, said hearth having a plurality of mold cavities;
- (c) a plasma jet torch having a tip and a nozzle located within said shell, and means for supplying inert gas past said tip through said nozzle into said shell;
- (d) means slidably and pivotally mounting said torch in a wall of said shell;
- (e) means for rotating said hearth to position a selected one of said plurality of mold cavities in position so that the effluent from said nozzle is directed onto metal to be melted in said selected mold cavity; and
- (f) means for evacuating said shell.

4. A furnace for melting metals comprising:

- (a) a sealed shell;

- (b) a rotatable, water-cooled horizontal hearth in said shell, said hearth having a plurality of mold cavities;
  - (c) a plasma jet torch having a tip and a nozzle located within said shell, and means for supplying inert gas past said tip through said nozzle into said shell;
  - (d) means slidably and pivotably mounting said torch in a wall of said shell;
  - (e) means for rotating said hearth to position a selected one of said plurality of mold cavities in position so that the effluent from said nozzle is directed onto metal to be melted in said selected mold cavity; and
  - (f) means for evacuating said shell.
- 5 5. A furnace as set forth in claim 4 including:
- (f) a glass viewing window in said shell, and a metal

screen interposed between the glass and the interior of said furnace shell.
